(57) **CLAIM**

The ornamental design for a multi-angled adjustable LED floodlight, as shown and described.

DESCRIPTION

FIG. 1 is a perspective view from the front and above of a multi-angled adjustable LED floodlight showing my new design;

FIG. 2 is a perspective view from the back and above of the multi-angled adjustable LED floodlight;

FIG. 3 is a back view of the multi-angled adjustable LED floodlight;

FIG. 4 is a front view of the multi-angled adjustable LED floodlight;

FIG. 5 is a left side view of the multi-angled adjustable LED floodlight;

FIG. 6 is a right side view of the multi-angled adjustable LED floodlight;

FIG. 7 is a bottom view of the multi-angled adjustable LED floodlight; and,

FIG. 8 is a top view of the multi-angled adjustable LED floodlight.

The broken lines shown are for illustrative purposes only and form no part of the claimed design.
